UNITED STATES PATENT OFFICE.

WILLIAM H. PEIRSON, OF ATLANTIC CITY, NEW JERSEY.

DESIGN FOR AN ELEVATOR-CAR.

SPECIFICATION forming part of Design No. 24,372, dated June 4, 1895.

Application filed December 17, 1894. Serial No. 532,108. Term of patent 14 years.

To all whom it may concern:

Be it known that I, WILLIAM H. PEIRSON, a citizen of the United States, residing at Atlantic City, in the county of Atlantic and State of New Jersey, have invented and produced a new and original Design for Elevator-Cars, of which the following is a specification, reference being had to the accompanying drawing.

10 The figure is an elevation of an elevator-car, showing my design.

The leading feature of my design consists in the specific shape of car shown in the drawing, wherein the lower part is pierced with

openings as shown, and the roof has the bulbous shape illustrated, the whole having the contour as shown.

The lower part of the car is shown at A in the drawing and the bulbous top at B. The lower part is provided with windows and doors as shown.

What I claim is—

The design for an elevator car, substantially as shown and described.

WILLIAM H. PEIRSON.
